UNITED STATES PATENT OFFICE.

VASIL RAYNOVITCH KOZLOFF, OF NEW YORK, N. Y.

GARMENT SUPPORTER.

Application filed April 27, 1921. Serial No. 464,899.

To all whom it may concern:

Be it known that I, VASIL RAYNOVITCH KOZLOFF, a citizen of the United States, and resident of the city of New York, borough 5 of Manhattan, county of New York, and State of New York, have invented a new and Improved Garment Supporter, of which the following is a full, clear, and exact description.

10 My invention relates to a garment supporter, and aims to provide certain new and useful improvements in connection with devices of this character as heretofore placed upon the market.

15 More particularly my present invention aims to provide a commercially practical supporter which will permit of the utilizing of suspenders, underneath the shirt, and in such a manner that they will support the 20 trousers without being visible, thus incorporating the slight appearance of a belt with the efficiency of suspenders.

A further object of this invention is the provision of a supporter which may be economically manufactured and, in which a 25 general structure will be provided which will render the same capable of being utilized by persons of various statures.

Further objects of this invention will appear in the annexed specification taken in connection with the drawings which latter present one practical embodiment of my invention, and in which:

Figure 1 shows a figure of a person and 35 indicating in dotted lines thereon the application of my invention.

Figure 2 is a partly fragmentary sectional side view taken along the line 2—2 of Figure 3.

40 Figure 3 is a transverse sectional view taken along the line 3—3 and in the direction of the arrows indicated in Figure 2.

45 Figures 4, 5 and 6 are detail views of the members providing the supporter and showing the same detached, and

Figure 7 is a sectional view taken along the line 7—7 of Figure 1.

Referring now more particularly to Figures 1 to 3 it will be seen that the reference 50 numeral 10 indicates trousers which are to be supported, and 11 a shirt associated with the body of the wearer, it being noted that suspenders 12 are utilized for supporting the trousers, these suspenders lying between the body of the wearer and the inner face of the shirt 11.

With a view of providing means which will serve to prevent any great amount of relative movement of the suspenders 12 with respect to the shirt 11 it will be seen reference being had to Figures 1 and 7 that a number of guide strips 13 are provided at the shoulder portions of the shirt, other strips being secured to the inner face of the shirt and rear of the shirt. The suspenders 60 pass through these strips and obviously this construction, together with the attaching of the outer ends of the suspenders to the shirt in the manner hereinafter more fully described, will prevent the suspenders from 65 shifting or turning aside from the fact that it will enable the same to remain on the shirt when the latter is removed from the body.

The supporting device itself embodies 70 two elements, to wit, a suspending and attaching element. Referring to the former, reference being had to Figures 2, 3 and 4, it will be seen that the same includes a preferably oblong body portion 14 which is constructed of wire, or other suitable material, and is formed with a bent part 15, at a point preferably intermediate its ends, said bent part providing a retaining member for the 75 second member of the suspending element. This member includes a body also preferably 80 of a single piece of wire, the ends of which are bent to provide a hook 16 adapted to co-operate with the bent portion 15, the body of said wire being bent to provide a diamond shaped element 17.

With regard to the attaching element, reference being had to Figures 2, 3, 5 and 6 it will be seen that the same also comprises an oblong body portion 18 preferably of wire, 85 which is bent at a point preferably intermediate its ends to provide hooks 19, it being noted that the body portion 18 is preferably curved throughout its entire length, and is formed with reduced portions 20 for a purpose hereinafter more fully stated.

In practice, the suspending element, including the body portion 14 is attached to the suspender 12 by passing one of the ends of the latter through the loop formed by the body portion thereof, as in Figure 3, and the attaching member, including the body portion 18 is associated with the waist band of the trousers by stitching co-operating with the reduced portions 20 or any other 100 suitable retaining means, it being noted in this connection that the curvature of the 105 body portion 18 is such that it will be held in place by the reduced portions 20.

body 18 is such as to conform to the waist band of the body of the trousers 10. In this connection it is also to be noted that the hook 19 is arranged so as to extend towards the waist band of the trousers, which by virtue of the fact that the trousers band is constantly being pressed to a point directly underlying the hook 19, prevents any accidental detachment of these portions from the elements 17 incident to a movement of the body.

Now with a view of permitting of the co-operation of the suspending element with the attaching element, and to also provide means which will serve to permit of the use of the device with trousers, having waist bands of varying heights, attention is invited to Figures 2 and 3. It will be seen in these views that the shirt 11 is formed at points adjacent the lower ends of the suspenders 12, with a series of openings 21 in the nature of button holes, these openings overlying each other. Thus the user is allowed a range of adjustment, in that he may pass the diamond shaped element 17 through any one of the openings 21 to bring the element 17 to a point most nearly adjacent the hook 19 of the attaching element.

In this connection it is to be noted that the peculiar shape of the member 16 is to be predicated to the fact that by utilizing an element of this nature, the wearer may readily pass the same through any of the openings 21, desired, but by virtue of this shape, any accidental withdrawal of the members 17 through the openings 21 with which it is associated, will be precluded, attention being invited to Figure 2.

Thus a supporting member is provided which will primarily provide a medium permitting of the ready attachment and detachment of a nether garment, with the same, the structure utilized being capable of being manufactured at an extremely nominal figure, it being further seen that by means of the strips 13 no stress will be felt by the wearer in that the suspenders are permitted to adjust themselves with respect to the body.

Furthermore a supporting member con-

structed in accordance with my invention will cause the shirt to lie far better than has heretofore been the case where either belts or suspenders were utilized, in that the suspender 12 includes the strips 13 of the shirt 11, thus being retained in place, and also holding the shirt properly, aside from the fact that the suspender again cooperates with the shirt at the openings 21.

Thus the objects, set forth in the preamble of this specification are accomplished, and it will be appreciated that modifications of structure might readily be resorted to without in the least departing from the scope of my claims, which are;

1. A garment supporter including a shirt, a suspending element and attaching element, said suspending element being adapted to be secured to the end of a suspender, said attaching element being secured to a nether garment, and adjacent the waist band of the same, and strips secured to said shirt for overlying said suspender, said suspender passing between said strips and shirt.

2. A garment supporter including a suspending element and attaching element, said suspending element being adapted to be secured to the end of a suspender, said attaching element being secured to a nether garment and adjacent the waist band of the same, a shirt adapted to over lie said suspender, said shirt being formed with a series of openings through one of which a portion of said suspending element is adapted to pass.

3. A garment supporter including a suspending element and attaching element, said suspending element being adapted to be secured to the end of a suspender, said attaching element being secured to a nether garment and adjacent the waist band of the same, a shirt adapted to over lie said suspender, said shirt being formed with a series of openings through one of which a portion of said suspending element is adapted to pass, and means forming a part of said suspending element for preventing an accidental retraction of said part through said opening.

VASIL RAYNOVITCH KOZLOFF.
